UNITED STATES PATENT OFFICE

ROBERT J. PRICE, OF PITTSBURGH, PENNSYLVANIA, ASSIGNOR TO PITTSBURGH PLATE
GLASS COMPANY, A CORPORATION OF PENNSYLVANIA

CAR COUPLING DEVICE

Application filed February 18, 1932. Serial No. 593,791.

This invention relates to car coupling apparatus designed particularly for coupling together the cars or tables employed in straight-away glass grinding and polishing operations. In such operations, the cars with the glass seated upon their upper faces, are moved in a continuous train beneath a series of grinding and polishing runners. It is necessary under these conditions that the cars be held tightly together so that their tops or faces constitute a continuous, unbroken surface, and that such faces be held flush with each other at their abutting ends. The primary objects of the present invention are to provide an improved means whereby these objects are accomplished, wherein the relative position of the car ends is maintained regardless of vibration or strain, and which will permit a ready coupling and uncoupling operation. Briefly stated, this is accomplished by the use of overlapping members arranged on the abutting car ends in connection with coupling devices which in addition to pulling the car ends tightly together applies a powerful pressure, forcing the upper one of the overlapping members against the lower one so that the car ends are securely held against relative vertical movement. Certain embodiments of the invention are illustrated in the accompanying drawings, wherein:

Figure 1 is a horizontal section in part on the line I—I of Fig. 2 and in part on the line I^a—I^a of Fig. 2. Fig. 2 is a section on the line II—II of Fig. 1. Fig. 3 is a side elevation. Fig. 4 is an end elevation. Fig. 5 is a diagrammatic perspective view. Fig. 6 is a detail perspective view. And Fig. 7 is a vertical section through a modification.

Referring to the drawings, 1 and 2 are the ends of abutting tables or cars provided with the wear plates where their tops engage. The tables are moved along the track 4 by means of racks 5 (Fig. 4) extending longitudinally of the middle of the tables and engaged by driven spur gears at suitable intervals. The ends of each pair of tables are provided with the overlapping members 6 and 7 faced with suitable wear plates and adapted to prevent the movement of the end

of the car 1 upward with respect to the end of the car 2 when the cars are in the coupled position shown in Fig. 3. Each pair of car ends is provided with two coupling devices, only one of which is shown in Figs. 1 and 2 since only half of the car is illustrated. It will be understood that the other side of the car is provided with a coupling means which is similar in all respects to the one which is illustrated and described. It will be further understood, however, that this is merely a preferred construction and that, if desired, the cars or tables may be coupled together by a single coupling device.

As indicated in Fig. 2, the car 2 is provided with an upwardly facing hook member 8 provided with a wear plate 9 and the car 2 is provided with a swinging hook member 10 which faces downwardly and is provided with a wear plate 11. The opposing engaging faces of the hook members lie at an angle of approximately 45 degrees so that when a pull is applied to the hook member 10 in the direction of its length, the car ends are pulled together and a lifting force is applied on the end of the car 1 tending to move it upward with respect to the end of the car 2, this upward movement being resisted by the overlapping members 6 and 7. The coupling, therefore, serves in connection with the overlapping members 6 and 7 to securely hold the car ends against relative vertical movement in addition to performing the function of securing the car ends against a horizontal movement of separation.

The hook member 10 is mounted eccentrically so that in the coupling operation it is first swung in a clockwise direction until its engaging face is in opposition to the engaging face of the hook member 8, after which the member 10 is moved in the direction of its length into engagement with the hook member 8. In uncoupling, a reverse movement occurs, the hook member 10 being first moved endwise to disengage it from the hook member 8, after which it is swung about its axis to a substantially vertical position. The hook member 10 is mounted upon a shaft having the central portion 12 which is eccentric with respect to the end portions 13,

13 (Fig. 1), the central portion 12 carries the hook member while the end portions 13, 13 are mounted for rotation in the ends of the lever 14. The lever 14 is fulcrumed on 5 the under side of the car at 15, at which point it is supported by means of the bolt 16. Its left hand end (Fig. 2) is held yieldingly in the position shown by means of the bolt 17 and spring 18. The eccentric shaft 12, 10 13 is rotated to secure a coupling and uncoupling action by means of a shaft 19 pivoted in the bearings 20, 20 and connected at its inner end to the shaft 12, 13 by means of a flexible coupling 21. Such flexible coupling 15 is necessary due to the fact that the lever 14 in which the shaft 12, 13 is journaled moves slightly in a vertical direction during the coupling action so that some relative movement must be provided between the 20 ends of the shafts 12, 13 and the shaft 19. The shaft 19 is oscillated by means of the lever 22 provided with the rollers 23 and 24 adapted to ride on the cam rails 25 and 26. While the roller 23 rides on the cam track 25, the parts of the coupling are held in the position indicated in Fig. 2. When the roller 23 is released from the rail 25 and the roller 24 is engaged by the inclined end of the rail 26 25 (Fig. 3), the lever 22 is swung in a counter clockwise direction to the position shown in Fig. 5, thus separating the coupling hooks. As indicated in Fig. 5, the lever 14 is provided with a pair of stop shoulders 27 which 30 serve to limit the downward swinging movement of the hook 10 when the car ends are separated. The hook 10 is thus always maintained at a sufficient height to properly engage with the hook 8 when the two cars 35 are caused to come into abutting relation. The shaft 12, 13 is also provided with a pair of hook lifting dogs 28, 28 as shown in Figs. 5 and 6, such dogs serving to engage the hub of the hook member 10 and swing 40 it to an upright position after the endwise movement of the hook has released its engaging face from the engaging face of the hook member 8. The parts are so arranged that when the hook member 10 is moved to 45 final coupling engagement as shown in Fig. 2, the shaft 12, 13 is moved bodily upward a slight distance causing a downward movement of the left hand end of the lever 14, thus increasing the compression of the 50 spring 18. A powerful yielding engagement is thus secured between the faces of the overlapping members 6 and 7. The cars or tables are held together with such security that in operation the upper faces of the cars 55 at their meeting ends are held perfectly flush so that, if desired, the glass which is to be ground may be laid over this joint.

Fig. 7 illustrates a modification which 60 accomplishes the same result as the construction of Figs. 1 to 6 and has the advantage

of being a simpler, cheaper construction. In this construction, the hook member 29 is pivoted upon an eccentric shaft 30 similar to the shaft 12, 13, but having its ends pivoted upon a bracket 31 rigidly secured to the bottom of the car end 32. The means for rotating the shaft 30 is the same as in the construction of Figs. 1 to 6, an operating shaft similar to the shaft 19 being employed which carries at its end the lever 33 provided with the rollers 34 and 35. These rollers engage cam rails corresponding to the cam rails 25 and 26 and the operation of the coupling due to the movement of the cars is the same as heretofore explained in connection with the other form of device. The hook member 40 on the end of the car 36 instead of being fixed as in the construction of Figs. 1 to 6 is pivoted to the car end at 37 and is held yieldingly in the position shown by means of the bolt 38 and spring 39. The two car ends are provided with overlapping members like the members 6 and 7 shown in Fig. 3 with the lower member corresponding to the member 7 on the end of the car 32. When the lever 33 is moved in a clockwise direction to the position shown in Fig. 7, the hook 29 is moved in the direction of its length so that the cars are pulled tightly together and force is applied downward on the hook 40 placing the spring 39 under compression and forcing the overlapping member on the car end 32 into tight engagement with its opposing member on the end of the car 36. The function accomplished in the construction is, therefore, precisely the same as that in the construction of Figs. 1 to 6.

Unless provision is made to avoid it, there would be a large amount of wear between the plates 6 and 7 (Fig. 3) and in the course of time lost motion would occur which would defeat the purpose of the overlapping devices. To take care of this difficulty, cams 40, 40 (Figs. 3 and 4) are provided along the sides of the tracks, and the flanges 41, 41 of the two wheels of the car which carry the upper plate 6 and lie adjacent such plate are of slightly greater diameter than that of the flanges of the wheels on the adjoining car, so that when the cars are brought to abutting relation preliminary to coupling, the plate 6 does not engage the plate 7. The same condition exists when the plates are uncoupled so that there is no wear at this point. When the coupling apparatus is operated the plate 7 is pulled up against the plate 6.

What I claim is:

1. In combination with a pair of abutting cars with overlapping members at the ends of the cars so that the car end carrying the lower of the two members is held positively against movement upward relative to the other car end, a pair of oppositely facing coupling hooks carried by the two car ends

one of which is fixed and the other is mounted for swinging movement, and operating means for the swinging hook arranged so that the actuation of the hook pulls the car ends horizontally against each other and exerts a yielding force vertically tending to press the upper of said overlapping members downward against the other of said members.

- 10 2. In combination with a pair of abutting cars with overlapping members at the ends of the cars so that the car end carrying the lower of the two members is held positively against movement upward relative to the other car end, a pair of oppositely facing coupling hooks carried by the two car ends one of which is fixed and the other is mounted for swinging movement, and operating means for the swinging hook arranged so
- 15 20 that the actuation of the hook pulls the car ends horizontally against each other and exerts a yielding force vertically tending to press the upper of said overlapping members downward against the other of said members, the engaging faces of the two hooks being inclined at an angle to the horizontal.
- 25

3. In combination with a pair of abutting cars, means for coupling them together, which comprises an upwardly facing hook member secured to the end of one car having its engaging face inclined forwardly and upwardly, a second hook member mounted for vertical swinging movement and for movement in the direction of its length on the end of the other car and adapted to engage the first hook member, said second hook member having its engaging face inclined at the same angle as that of the first hook member when in engaging position, operating means for swinging the second hook member adapted to move such member in the direction of its length after it has been swung so that the engaging faces of the hook members are in opposition, and yielding means cooperating with one of said hook members and placed under stress by the movement of the second hook member in the direction of its length.

50 4. In combination with a pair of abutting cars, means for coupling them together, which comprises an upwardly facing hook member secured to the end of one car having its engaging face inclined forwardly and upwardly, a support carried by the end of the other car and yieldingly held against upward movement, a second hook member pivoted on the support for vertical swinging movement and for movement in the direction of its length and adapted to engage the first hook member, said second hook member having its engaging face inclined at the same angle as that of the first hook member when in engaging position, and operating means for swinging the second hook

55

60

65

member adapted to move such second hook member in the direction of its length after it has been swung so that the engaging faces of the hook members are in opposition.

5. In combination with a pair of abutting cars, means for coupling them together, which comprises an upwardly facing hook member secured to the end of one car having its engaging face inclined forwardly and upwardly, a second hook member mounted for vertical swinging movement and for movement in the direction of its length on the end of the other car and adapted to engage the first hook member, said second hook member having its engaging face inclined at the same angle as that of the first hook member when in engaging position, operating means for swinging the second hook member adapted to move such member in the direction of its length after it has been swung so that the engaging faces of the hook members are in opposition, and yielding means for holding the first hook member against downward movement. 70
75
80
85

6. In combination with a pair of abutting cars, means for coupling them together, which comprises an upwardly facing hook member secured to the end of one car having its engaging face inclined forwardly and upwardly, a second hook member 95 mounted for vertical swinging movement and for movement in the direction of its length on the end of the other car and adapted to engage the first hook member, said second hook member having its engaging face inclined at the same angle as that of the first hook member when in engaging position, and operating means for swinging the second hook member arranged to move such member in the direction of its length 100 after it engages the first hook member, said first hook member being pivoted at one end to the car end and spring held against downward movement about its pivot. 105

7. In combination with a pair of abutting cars, means for coupling them together, which comprises an upwardly facing hook member secured to the end of one car having its engaging face inclined forwardly and upwardly, a second hook member mounted for vertical swinging movement and for movement in the direction of its length on the end of the other car and adapted to engage the first hook member, said second hook member having its engaging face inclined at the same angle as that of the first hook member when in engaging position, operating means for swinging the second hook member adapted to move such member in the direction of its length after it has been swung so that the engaging faces of the hook members are in opposition, overlapping means at the opposing ends of the cars preventing the upward movement of the car end carrying the second hook member with 130

respect to the other car end, and yielding means cooperating with one of said hook members and placed under stress by the movement of the second hook member in the direction of its length.

8. In combination with a pair of abutting cars, means for coupling them together, which comprises an upwardly facing hook member secured to the end of one car having its engaging face inclined forwardly and upwardly, a support carried by the end of the other car and yieldingly held against upward movement, a second hook member pivoted on the support for vertical swinging movement and for movement in the direction of its length and adapted to engage the first hook member, said second hook member having its engaging face inclined at the same angle as that of the first hook member when in engaging position, overlapping means at the opposing ends of the cars preventing the upward movement of the car end carrying the second hook member with respect to the other car end, operating means for swinging the second hook member adapted to move such second hook member in the direction of its length after it has been swung so that the engaging faces of the hook members are in opposition.

30 9. In combination with a pair of abutting cars, means for coupling them together, which comprises an upwardly facing hook member secured to the end of one car having its engaging face inclined forwardly and upwardly, a second hook member mounted for vertical swinging movement and for movement in the direction of its length on the end of the other car and adapted to engage the first hook member, said second hook member having its engaging face inclined at the same angle as that of the first hook member when in engaging position, operating means for swinging the second hook member adapted to move such member in the direction of its length after it has been swung so that the engaging faces of the hook members are in opposition, overlapping means at the opposing ends of the cars preventing the upward movement of the car end carrying the second hook member with respect to the other car end, and yielding means for holding the first hook member against downward movement.

10. In combination with a track and a pair of abutting cars thereon with overlapping members at the ends of the cars so that the car end carrying the lower of the two members is held positively against movement upward relative to the other car end, flanges on the wheels of the car end having the upper overlapping member which have a diameter greater than that of the wheels of the opposing car end, cam means along the sides of the rails constituting the track for engaging the flanges of the pair of

wheels having the flanges of greater diameter, and means for coupling the car ends together.

In testimony whereof, I have hereunto subscribed my name this 2nd day of February, 1932.

ROBERT J. PRICE.
